UNITED STATES PATENT OFFICE.

NORMAN G. BAKER, OF MUSCATINE, IOWA.

TRACKER BAR.

Application filed January 22, 1925. Serial No. 4,051.

This invention is an improvement in tracker bars for automatic musical instruments, such as pianolas, band organs, and the like, and the principal object thereof is to provide a tracker bar, made in two separable sections and having a removable dust screen interposed between the sections, with novel means for readily and quickly locking or unlocking the sections, in order that the dust screen may be readily removed for cleaning.

I will explain the invention with reference to the accompanying drawing which illustrates one practical embodiment thereof to enable others to adopt and use the same, and will summarize in the claims the novel features of construction, and novel combinations of parts, for which protection is desired.

In said drawings:

20 Figure 1 is a perspective view of a tracker bar showing the two sections thereof locked together.

Figure 2 is an enlarged side elevation of the same, showing the two sections in unlocked position.

Figure 3 is a transverse section through the tracker bar.

The tracker bar, as shown, is made in two separable sections, a lower section 1, and 30 upper or outer section 2. The lower section 1 is adapted to be mounted in any desired manner upon the projecting portion A of the frame of the instrument, the outer surface thereof being flat and provided with 35 one or more rows of perforations 1^b connected in the usual manner to the key, or note, suction tubes A' of the instrument.

The outer section 2 of the tracker bar, preferably made of brass, is likewise provided with one or more rows of perforations 2^b adapted to normally register with the perforations 1^b in section 1, when the sections are locked together, and the outer face of section 2 is preferably smooth and slightly rounded for the perforated paper music roll (not shown) making a sliding contact therewith in the usual manner.

50 Protruding from the outer face of section 1 at opposite ends thereof are two alignment pins 1^c adapted to engage holes 2^a in the under side of the outer section 2 when the two sections are super-imposed to insure that the two sections, when locked together, will be properly aligned, with the perforations 2^b in section 2 registering with their respective perforations 1^b in section 1.

A dust screen 3 of fine mesh, and preferably of same area as the opposed faces of the tracker bar sections is interposed between the two sections 1 and 2, and also between two gaskets 3^a and 3^b, preferably of soft leather, mounted upon the adjacent faces of their respective sections 1 and 2, said gaskets having perforations therein registering with those in the sections 1 and 2 and also having perforations for the passage therethrough of the alignment pins 1^c of section 1, so that when the screen is interposed between the gaskets on sections 1 and 2, and the sections locked together, as hereinafter described, air will be prevented from entering the perforations around the screen 3 between the sections, while permitting air to enter the outer ends of perforations 2^b in the tracker bar when the perforations 75 in the paper music roll register therewith, the air passing through the screen 3 before passing into the tubes A' of the instrument.

The dust screen 3 must be removed for the purpose of cleaning, and for this purpose I have provided novel sliding cam plates for detachably connecting the sections 1 and 2 together. As shown, a plate 4 is slidably mounted on each side of the tracker bar, each plate 4 having elongated slots 4^c, therein adjacent their lower edges through which extend screws or headed pins 4^b, projecting from the sides of section 1, thereby permitting plates 4 to slide longitudinally of the tracker bar, handles or projections 4^c being formed or provided on the plates to facilitate the movements thereof, but preventing transverse movement of the plates with respect to the tracker bar. Extending downwardly from the upper edge of each plate 4 are a plurality of parallel angularly disposed cam slots 4^d, three being shown on each plate 4, adapted to receive pins or studs 4^e projecting from the sides of the outer section 2, whereby when the sections 1 and 2 are placed together, with alignment pins 1^c of section 1 entering the holes 2^a in section 2, as the plates 4 are moved in one direction (toward the left in Fig. 2) the pins 4^e will enter their respective slots 4^d, and 105 will be drawn downwardly by said slots, thereby locking the two sections together, and retaining the same in locked position, with the screen 3, and gaskets 3^a and 3^b, interposed therebetween; but when the plates 4 are moved on the opposite direction, the pins 4^e will be forced upwardly, and will 110

pass out of said slots 4^a thereby unlocking fixed section, and having a plurality of parallel angularly disposed cam slots therein extending inwardly from the edge, adjacent the removable section; and pins on the removable section adapted to engage said slots.

5 the same may be placed upon the section 1 and section 2 super-imposed thereon with the pins 1^c of the lower section entering the holes 2^a in section 2, and the two sections then locked together by means of the cam 10 plates 4, as above described.

15 My novel means for locking the two separable sections of the tracker bar together is simple and efficient, and permits the sections being readily unlocked in order to permit removal of the screen for the purpose 20 of cleaning same.

I do not limit my invention to the exact form shown in the drawing, for obviously minor changes may be made therein within 25 the scope of the invention.

I claim:

1. A tracker bar comprising two separable sections, a screen between said sections, cam 25 means for detachably locking said sections together comprising a plate longitudinally slidably mounted on the side of one section and having one or more angularly disposed cam slots therein extending inwardly from one edge and overlying the other section, 30 and one or more pins on the other section adapted to engage said slots.

2. A tracker bar comprising two separable sections; a dust screen interposed between said sections; and a slidable cam for detachably locking said sections together, said means comprising a plate movably mounted on one section, and having a plurality of parallel angularly disposed cam slots extending inwardly from one edge adjacent the other section, and pins on the other section adapted to engage said slots.

3. A tracker bar comprising a fixed section; a removable section; a dust screen interposed between said sections; and slidable cam means for detachably locking said sections together, said means comprising plates longitudinally movably mounted on the

50 fixed section, and having a plurality of parallel angularly disposed cam slots therein extending inwardly from the edge, adjacent the removable section; and pins on the removable section adapted to engage said slots.

4. A tracker bar for musical instruments comprising a fixed section adapted to be mounted on the said instrument; a removable section adapted to be mounted on said fixed section; a dust screen removably interposed between said sections; means for aligning said sections; and slidable cam means for detachably locking said sections together, said means comprising plates longitudinally movably mounted on the fixed section, each plate having a plurality of parallel angularly disposed cam slots therein extending inwardly from the edge adjacent the removable section; and pins on the removable section adapted to engage said slots.

5. A tracker bar for musical instruments comprising a fixed section adapted to be mounted on said instrument; a removable outer section adapted to be mounted on said fixed section; a dust screen removably interposed between said sections; means for aligning said sections; gaskets interposed between said screen and sections; and slidable cam plates on each side of said tracker bar for detachably locking said sections together, said cam plates having longitudinal slots therein adjacent the fixed section; headed pins on said fixed section engaging said slots whereby said plates will be longitudinally mounted on said fixed section; said plates each having a plurality of parallel angularly disposed cam slots extending inwardly from the edge adjacent said removable section; pins on the removable section adapted to engage said cam slots; and handles on said plates for moving same.

In testimony that I claim the foregoing as my own, I affix my signature.

NORMAN G. BAKER.
